NICHOLAS S. VEDDER, OF TROY, AND TOBIAS S. HEISTER, OF LANSINGBURG, NEW YORK, ASSIGNEES TO NICHOLAS S. VEDDER.

Design No. 3,864, dated February 22, 1870.

DESIGN FOR A STOVE-PLATE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer, and State of New York, have jointly invented and produced a new and original Design for Plates or Castings of a Parlor-Stove, of which the following is a specification, reference being had to the accompanying photographic illustration.

Our new design for the bottom plate *i*, end door or plate *j*, lower front doors *k*, upper front doors *l*, front plate *m*, top plate *n*, and open-work cover *o* of a

parlor-stove, is shown in the aforesaid photographic representation.

What we claim as our invention and production, and desire to secure by Letters Patent, is—

The design for the above-named parts of a parlor-stove, as shown in the aforesaid photographic illustration.

NICHOLAS S. VEDDER.
